CHIMNEY ATTACHMENT

Armin Burger, Bern, Switzerland

Application November 1, 1954, Serial No. 466,184

Claims priority, application Switzerland
November 2, 1953

2 Claims. (Cl. 98—78)

The present invention relates to a chimney attachment with at least two mutually superimposed nozzle bodies, which between one another form wind conducting conduits leading from the outside inwardly and upwardly.

The invention has the primary object of providing a chimney attachment of the kind referred to wherein rain water which may have entered the chimney attachment is safely drained off laterally and thereby prevented from entering the chimney stack.

With this and other objects in view I provide a chimney attachment comprising in combination:

At least two super-imposed nozzle bodies forming between them wind guiding conduits directed inwardly and upwardly from outside, and an air distributor body arranged in a vertical middle plane of the chimney attachment between at least two mutually opposite inner orifices of said wind-guiding conduits, the said air distributor body being symmetrical with respect to the said vertical middle plane and having an upper central web with concave faces curving outwardly, the cross section area of the portion of the said air distributor body below the said central web diminishing from the end faces towards the middle of the said portion.

Any rain water adhering to the said air distributor body runs from the reduced inner part of said lower portion down towards the enlarged end faces thereof, and can be drained off from there to the outside of the chimney attachment.

These and other objects and features of my said invention will be clearly understood from the following description of an embodiment thereof given by way of example with reference to the accompanying drawing, in which:

Fig. 1 shows a longitudinal section through a row of chimneys;

Fig. 2 is a section taken along the line II—II of Fig. 1;

Fig. 3 is a perspective view of a member shown in Figs. 1 and 2; and

Fig. 4 is a section of a chimney cowl having wind passages on all four sides.

The chimney stake shown in Fig. 1 comprises three chimneys 1, 2, 3, side by side, on each of which are separate cowls built up of three hollow cowl members 11, supported one on top of the other. On two opposite sides of the cowl between the members 11, are inwardly and upwardly inclined air passages 12 (Fig. 2) while on the other opposite pairs of sides there are plain walls 14. Between the masonry portions 10 of the chimney and the lowest cowl member 11 truncated conical or pyramidal pieces 101 are inserted which support the lowest cowl member and which have water drip ledges 102 projecting outwardly. In the longitudinal plane of symmetry of the row of chimneys air distributor bodies or elongated deflecting members 13 are provided which are shaped symmetrically to this longitudinal plane and to a vertical plane of symmetry passing through the longitudinal center of the deflecting member 13. Each deflecting member 13 has an upper middle web 130 with flank faces 131 respectively located on either side of the longitudinal plane of sym-

2

metry and curving concavely downwards and outwards and designed for deflecting descending winds into the wind conducting conduits 12. Each of the elongated deflecting members 13 have also a pair of oppositely arranged lower side portions 133 tapering toward a longitudinal plane of symmetry of the deflecting members 13 to form a sharp bottom edge 134 which is inclined downwardly and outwardly from the center of the deflecting member towards the end faces 135 thereof. The side portions 133 are respectively directed toward the air passages 12 as can be clearly seen from Fig. 2. The edge at which the upper face 130 meets with the faces on the lower portions 133 of the deflecting member diverges from a plane of symmetry passing through the center of the deflecting member and substantially normal to forementioned longitudinal plane of symmetry thereof towards the opposite ends of the deflecting member 13. The cross-section taken through the lower portion 133 of the deflecting member at this transverse plane of symmetry has therefore a smaller area than the end faces 135 of the deflecting member. The lower side portions 133 are designed conduits to prevent a non-permissible reinforcement of the draught through strong side winds flowing through the air passage 12, by deflecting these air flows and to reduce the draught effect through the formation of eddies. When the weather is becalmed or the wind velocities are low they are ineffective in this sense, and do not hamper the flow of the smoke, since the plan view area of the distributor bodies 13 is smaller than the area of the chimney aperture.

The aforesaid intersecting edge 134 of the distributor body extends with opposite free end portions thereof over drain conduits or channel means 136 and edge 134 is designed to divert rain water into drain conduits 136 on the front faces of opposite inner faces 14 of the chimney. These drain conduits 136 have a slope towards at least one of the two lateral faces of the chimney, so that they drain the water into the air conducting conduits 12 and prevent it from penetrating into the chimney.

The end faces of the upper web 130 of the deflecting members 13 are outwardly inclined and rest against the inner top edges of the walls 14, as shown in Fig. 1, so that the members 13 are securely mounted on the chimney. The end faces may also be stopped and rest in appropriately shaped cutouts formed in the upper portion of the chimney structure, as shown in Fig. 4.

A chimney attachment constructed in the manner described secures practically equal draught conditions at calm weather, with strong lateral winds and descending winds, which is very important as regards the adjustment of the stoves.

While I have herein described and illustrated in the accompanying drawings what may be considered a typical and particularly useful embodiment of my said invention, I wish it to be understood that I do not limit myself to the particular details and dimensions described and illustrated for obvious modifications will occur to a person skilled in the art.

What I claim as my invention and desire to secure by Letters Patent, is:

1. In a chimney structure in combination, a rectangular chimney top including two pairs of oppositely arranged wall portions, one pair of said oppositely arranged wall portions being formed with inwardly and upwardly directed air passages; channel means on the inner face of the other pair of said oppositely arranged wall portions inclined toward and communicating with said inwardly and upwardly directed passages in said one pair of oppositely arranged wall portions; and an elongated deflecting member located in said top portion of said chimney structure and extending between said other pair of oppositely arranged wall portions and having a pair of oppositely arranged lower side portions tapering toward the longi-

tudinal plane of symmetry of said deflecting member to form a sharp bottom edge, said bottom edge being inclined downwardly and outwardly from the center of said deflecting member toward and extending with opposite free end portions thereof, respectively over said channel means on the inner face of said other pair of oppositely arranged wall portions thereof, whereby rain water collecting on said deflecting member will be directed into said channel means and by the same into said passages and outwardly of said chimney structure.

2. In a chimney structure in combination, a rectangular chimney top including two pairs of oppositely arranged wall portions, one pair of said oppositely arranged wall portions being formed with a plurality of superimposed inwardly and upwardly directed air passages; channel means on the inner face of the other pair of oppositely arranged wall portions inclined toward and communicating, respectively, with a pair of said inwardly and upwardly directed passages in said one pair of oppositely arranged wall portions; and an elongated deflecting member located in said top portion of said chimney structure symmetrically with respect to a first vertical plane of symmetry through the longitudinal center of said deflecting member and a second vertical plane of symmetry transverse to said first plane of symmetry at the center of said deflecting member and extending between said other pair of oppositely arranged wall portions,

said deflecting member having on either side of said first plane of symmetry an upper face curving downwardly and outwardly and a lower face converging from the lower edge of the upper face toward said first plane of symmetry and lying substantially opposite the inner end of one of said inwardly and upwardly directed air passages, the edge at which said upper and lower faces meet diverging from said second plane of symmetry toward the ends of said deflecting member, and the edge in said first plane of symmetry at which the lower faces of said deflecting member meet being inclined downwardly from said second plane of symmetry toward the ends of said deflecting member, said ends of said deflecting member extending over said channel means, whereby rain water collecting on said upper faces of said deflecting member will be directed into said channel means and by the same into said passages and outwardly of said chimney structure.
